(57) **CLAIM**

The ornamental design for a skimmer lid for swimming pools, as shown and described.

DESCRIPTION

FIG. 1 is a perspective view of my skimmer lid for swimming pools;

FIG. 2 is a bottom perspective view of the skimmer lid of FIG. 1;

FIG. 3 is a top plan view of the skimmer lid of FIG. 1;

FIG. 4 is front elevation view of the skimmer lid of FIG. 1, wherein the side and rear elevation views are the same; and,

FIG. 5 is a bottom plan view of the skimmer lid of FIG. 1. The broken lines shown in the drawings illustrate portions of my skimmer lid for swimming pools that form no part of the claimed design.

1 Claim, 4 Drawing Sheets
